UNITED STATES PATENT OFFICE

STANLEY K. SMITH, OF WESTFIELD, MASSACHUSETTS, ASSIGNOR TO THE H. B. SMITH COMPANY, OF WESTFIELD, MASSACHUSETTS, A CORPORATION OF MASSACHUSETTS

COMBUSTION APPARATUS

Application filed May 24, 1929. Serial No. 365,629.

This invention relates to combustion apparatus, and more particularly to boilers, for example of the type employed for domestic heating such as is shown in my copending application, Serial No. 239,969, filed December 14, 1927. More particularly the present invention provides improvements facilitating the care and ordinary repairs of a heater or boiler of this character. Thus in accordance with this invention, improved means are provided to permit the ready repair or replacement of parts and to afford more ready accessibility to the interior of the boiler for cleaning. For example, the grate bars are arranged in conjunction with an operating link so that the latter, when normally positioned, is effective in holding the bars in operative position, means exterior of the ashpit being provided to hold the link in normal position but readily permitting its movement out of this position so that any one of the grate bars may be removed or replaced. Preferably the retaining means for the operating link may be released by the use of such a simple tool as a screw driver or the like. Furthermore this arrangement serves positively to hold both ends of the grate bars in place, thus preventing the wedging of clinkers or other foreign matter between the bars and their supports and the possible resulting interference with normal movement of the grate bar assembly. This invention also provides an improved clean-out door which affords access to the interior of the boiler and which, while positively held in position, may be readily removed by the turning of a single hand knob without requiring any tools. A further aspect of the invention relates to an improved means for connecting a damper to a control chain or the like which prevents catching or snarling of the chain and thus facilitates operation of the boiler.

In the accompanying drawings, Fig. 1 is a front elevational view of the improved boiler; Fig. 2 is a rear elevational view of the same; Fig. 3 is an end view of one grate bar with the operating crank integral therewith;

Fig. 4 is a broken side elevational view of the same;

Fig. 5 is a view of the opposite end of the bar;

Fig. 6 is a side elevational view of the ashpit with a portion of its wall broken away to show the grate bar supporting and operating means;

Fig. 7 is a broken section on line 7-7 of Fig. 6;

Fig. 8 is a broken elevational view of the front of the ashpit;

Figs. 9 and 10 are detail views showing the retaining means for the grate operating link in its released and normal positions respectively;

Fig. 11 is an elevational view of a portion of a damper or closure member with a control element projecting therefrom before the latter has been twisted to its normal position;

Fig. 12 is a similar view showing the control element in its final or normal position;

Fig. 13 is a side elevation showing the same in conjunction with a control chain;

Fig. 14 is an elevational view of a clean-out door;

Fig. 15 is a sectional view through such a door and a portion of the boiler supporting the same;

Fig. 16 is a sectional detail of a portion of the door and related parts; and

Fig. 17 is a sectional detail of the rear of the ashpit.

Referring to the accompanying drawings, the boiler proper is designated by the numeral 1, and the ashpit upon which the boiler rests is indicated by numeral 2. The front of the boiler is provided with the conventional fuel door 9 giving access to the interior combustion chamber which is connected by suitable internal flues 10 which communicate with the smoke bonnet 18 mounted upon the rear of the boiler proper.

This bonnet is connected to the funnel or smoke pipe 19 leading to the stack. The bonnet 18 may be provided with the usual cold air inlet door 21 as well as a damper, etc., not shown. A sliding damper 27 is supported

upon suitable guides at the back of the

100

furnace for affording additional control of combustion as set forth more particularly in my above-identified application.

As shown in Fig. 7, a pair of supporting angles 20 may extend along opposite sides of the interior of ashpit 2 which is provided with the usual clean-out door 4. These angles are provided with a plurality of integral bosses 22 which may be engaged by socket portions of the grate bars. One of the latter is illustrated more particularly in Figs. 3, 4 and 5 and comprises a body portion 23 having outstanding parallel grate elements 24 and an integral depending crank arm 25 provided with a crank portion 26. One end of each grate bar is provided with a cylindrical recess or socket 29 adapted to receive one of the bosses 22 while the opposite end of the grate bar, i. e. that adjoining the crank, is provided with a socket portion 30 which is open at its lower end; i. e. this socket is provided by a substantially U-shaped wall 31 which is adapted to fit over the corresponding boss 22 of the supporting angle. An operating link 32 extends through the ashpit, being provided with a plurality of equally spaced openings 34 (Fig. 6) each adapted to receive one of the cranks 26. The link 32 ordinarily engages the cranks and holds them down so that the bars may not be lifted out of engagement with the bosses 22, while at the same time the bars may be rocked by the reciprocating movement of the link. To this end a suitable bracket 40 projects outwardly from the bottom of the ashpit, this bracket being provided with spaced projecting arms 41 having aligned openings to receive a pin 42 forming a pivot for a control lever 44 normally adapted to swing from front to rear through a limited pivotal path. Lever 44 is provided with a slot 45 engaging a pin 46 which also passes through an opening in the outer end of link 32. Link 32 extends through openings 50, in the front and rear respectively of the ashpit, which are so shaped and dimensioned that they will permit lateral bodily movement of the link out of engagement with end portions of the crank members. Preferably arms 41 upon the bracket 40 have their inner faces provided with surfaces which are inclined to each other and are angularly disposed in relation to the axis of pin 42. The pivot pin 42 fits loosely in the pivot opening at the lower end of lever 44 and thus the lever is adapted to be rocked out of its normal position indicated by dot and dash lines in Fig. 10, to the position illustrated in Fig. 9, thereby carrying the link 32 out of engagement with the crank elements. A retaining plate 51 normally is positioned over the opening 50 and is provided with a narrow slot 52 adapted to hold the link 32 in its normal position to prevent such a rocking movement.

The lower portion of the slotted plate 51 is provided with a protuberance 53 which engages a suitable slot 54 in the upper portion of the part of the bracket 40 that is engaged with the wall of the ashpit; for example, this recess may form a continuation of one of the openings through which extends one of the fastening elements holding this bracket to the ashpit. The upper portion of the plate 51 preferably is held in place by a single screw 54 or the like.

A similar plate 51 is disposed over the opening 50 at the back of the ashpit to hold the rear portion of the operating link in place, this cover plate having its protuberance 53 (Fig. 17) engageable with a recess in an integral extension 57 of the ashpit wall and being held in place by a single screw 54.

It is thus evident that removal of the two fastening elements 54, which may be accomplished by a commonplace tool such as a screw driver, permits the plates 51 to be swung out of their normal positions so that the lower end of lever 44 may swing about pin 42 until stopped from further movement by the lugs 41, thus swinging the link 32 to the position shown in Fig. 8 out of engagement with the cranks 26, permitting ready removal of the grate bars for repairs, replacement, or the like.

The ashpit preferably is provided with a rear draft door or closure 60 which is connected to a regulator such as a heat responsive member 61, for example, a diaphragm. Preferably the door 60 may be formed of cast metal having a strip S of comparatively ductile sheet metal embedded therein when the door is cast, such strip, for example, initially occupying the position illustrated in Fig. 11. A suitable opening 69 is punched in the outer end of this member S, after the door has been cast, the strip may be twisted to the shape shown in Figs. 12 and 13. A control chain 63 may be operatively connected to the regulator to swing the door in response to the position of the regulator as determined by the temperature of the boiler. The lower end of the chain 63 is provided with a suitable abutment member 64 that has a larger diameter than opening 69 so that it may engage the strip S to open the door when the chain is pulled upwardly. Catching or snarling of the chain is avoided by this arrangement.

A plurality of clean-out doors 70 are disposed adjoining the flues 10 in the upper part of the boiler. These doors preferably are mounted on metal frames 71 disposed about each of the door openings and secured to the body portion of the boiler. These frames preferably are provided with inturned flange portions 73 and with a continuous plane face 74 which engages the outer portion of the door 70. Each door preferably comprises an

outer dished portion 75 having suitable inwardly extending lugs 76 and a fire-shield 77 held by bolts 78 against the lugs. Preferably the lower edge of the shield 77 is provided with an inwardly and downwardly curved lip 81 that is adapted to hook over the inwardly extending flange 73 upon the frame 71, while a hand knob 80 is pivotally mounted in the plate 75 and projects through a suitable opening in the shield 77 and carries an eccentrically mounted lug 79 which is engageable with a downward extension of the flange 73 when the knob is turned to proper position. However, by turning the knob, the upper part of the door may be moved away from the frame and the lip 81 may be lifted out of engagement with the frame and the door entirely removed. Accordingly, manipulation of but a single fastening means is necessary to detach the door from the boiler housing while the comparatively heavy lug 79 and the lip 81 afford means firmly retaining the door in place while adjustment of the bolt 78 compensates for wear or slight warping. Any suitable means may be afforded for mounting the door frame upon the boiler housing. Thus in Fig. 16, for example, I show screw elements 91 which may be threaded into nut members 93 that are embedded in the furnace wall, these screw members passing through enlarged portions 90 of an outwardly projecting flange upon the frame in order to hold the latter in place. It is thus evident that the present invention affords an improved structural arrangement of boiler parts which facilitates the care and ordinary repair and replacement of parts.

I claim:

1. Combustion apparatus of the class described comprising a housing, a plurality of grate bars extending across the same, said grate bars being mounted for limited pivotal movement, a link normally holding the bars in place, and retaining means exterior of the ash-pit holding the link in normal position wherein it operatively engages the bars to impart movement thereto, said retaining means being removable, whereby the link may be moved out of its normal position to allow the bars to be removed.

2. Combustion apparatus comprising an ash-pit, a plurality of grate bars mounted therein, supporting means therefor at opposite sides of the pit, the ends of said bars being pivotally mounted and having a loose interfitting engagement with said supporting means, means for oscillating the bars operatively connected thereto and holding them in said interfitting engagement, and a retaining element exterior of the ash-pit holding said last-named means in normal position, the release of said means from the element permitting the bars to be removed from their engagement with the supporting means.

3. Combustion apparatus comprising an

ash-pit, a plurality of grate bars extending transversely thereof, supporting elements disposed along each side of the ash-pit, said elements having an interfitting engagement with end portions of the grate bars, but permitting the latter to be lifted out of engagement with the elements, a crank carried by each grate bar, and an operating link articulated to the cranks and normally holding the bars in place, said link passing through an opening at the front of the ash-pit, removal of the link from its normal position serving to disengage it from the several cranks, whereupon any one of the bars may be lifted out of its operative position.

4. Combustion apparatus comprising an ash-pit, a plurality of grate bars extending transversely thereof, supporting elements disposed along each side of the ash-pit, said elements having an interfitting engagement with end portions of the grate bars, but permitting the latter to be lifted out of engagement with the elements, a crank carried by each grate bar, an operating link articulated to the cranks and normally holding the bars in place, said link passing through an opening at the front of the ash-pit, the opening being of sufficient width to permit movement of the link to engage it with or disengage it from the cranks, and means normally retaining the link at such a part of the opening as to prevent its disengagement from the cranks.

5. Combustion apparatus comprising an ash-pit, a plurality of grate bars extending transversely thereof, supporting elements disposed along each side of the ash-pit, said elements having an interfitting engagement with end portions of the grate bars, but permitting the latter to be lifted out of engagement with the elements, a crank carried by each grate bar, an operating link articulated to the cranks and normally holding the bars in place, said link passing through an opening at the front of the ash-pit, the opening being of sufficient width to permit movement of the link to engage it with or disengage it from the cranks, a plate covering the opening, said plate having a slot forming a guide for the link through which the link extends, and releasable means normally holding the plate in fixed position, movement of the plate out of its normal position permitting the link to be removed laterally and thereby disengaged from the cranks, so that any selected one of the grate bars may be removed.

6. Combustion apparatus comprising an ash-pit, a plurality of grate bars extending transversely thereof, supporting elements disposed along each side of the ash-pit, said elements having an interfitting engagement with end portions of the grate bars but permitting the latter to be lifted out of engagement with the elements, a crank carried by each grate bar, an operating link articulated

to the cranks and normally holding the bars in place, said link passing through an opening at the front of the ash-pit, the opening being latterly wider than the link to permit the latter to be moved out of engagement with the cranks, a plate over said opening, said plate having a guide slot for the link, means normally holding the plate in fixed position, movement of the plate out of its normal position permitting the link to be removed laterally and thereby disengaged from the cranks, so that any selected one of the grate bars may be removed, and means at the rear of the ash-pit to permit a similar movement of the rear portion of the link.

7. Combustion apparatus comprising an ash-pit, a plurality of grate bars extending transversely thereof, supporting elements disposed along each side of the ash-pit, said elements having an interfitting engagement with end portions of the grate bars, but permitting the latter to be lifted out of engagement with the elements, a crank carried by each grate bar, an operating link articulated to the cranks and normally holding the bars in place, said link passing through an opening at the front of the ash-pit, the opening being of larger size than the link, a plate pivotally mounted over said opening, said plate having a guide opening through which the link extends, a single fastening element normally restraining the link from pivotal movement, the removal of said fastening element permitting the movement of the plate out of its normal position, thereby permitting the link to be moved laterally to disengage it from the cranks, so that any selected one of the grate bars may be removed.

8. Combustion apparatus comprising an ash-pit, a plurality of grate bars extending transversely thereof, supporting elements disposed along each side of the ash-pit, said elements having an interfitting engagement with end portions of the grate bars, but permitting the latter to be lifted out of engagement with the elements, a crank carried by each grate bar, an operating link articulated to the cranks and normally holding the bars in place, said link passing through an opening at the front of the ash-pit, the opening being of larger size than the link, a plate pivotally mounted over said opening and providing a guide opening through which the link extends, a single fastening element normally restraining the link from pivotal movement, the release of the fastening element permitting the movement of the plate out of its normal position, thereby allowing the link to be removed laterally to disengage it from the cranks, so that any selected one of the grate bars may be removed, the back of the ash-pit having an opening similar to that in its front, and a similar plate similarly mounted having a guide opening through which the rear of the link extends.

9. Combustion apparatus comprising an ash-pit, a plurality of grate bars extending transversely thereof, supporting elements disposed along each side of the ash-pit, said elements having an interfitting engagement with end portions of the grate bars, but permitting the latter to be lifted out of engagement with the elements, cranks carried by the grate bars, an operating link articulated to the cranks to hold the bars in place and normally passing through an opening at the front of the ash-pit, said opening being of larger size than the link, a plate pivotally mounted over said opening, said plate having a guide opening through which the link extends, fastening means normally restraining the plate from pivotal movement, said plate, when moved out of normal position permitting the link to be moved laterally and thereby disengaged from the cranks, so that any selected one of the grate bars may be removed, a lever connected to the link to rock the grate bars, a bracket upon the front of the ash-pit upon which the lever is mounted, said bracket having a portion in loose interfitting engagement with a portion of the plate whereby the latter may be pivoted when the single fastening means is released.

10. Combustion apparatus comprising an ash-pit, a plurality of grate bars extending transversely thereof, supporting elements disposed along each side of the ash-pit, said elements having an interfitting engagement with end portions of the grate bars, but permitting the latter to be lifted out of engagement with the elements, a crank carried by each grate bar, an operating link articulated to the cranks and normally holding bars in place, said link passing through openings at the front and rear, respectively, of the ash-pit, said openings being of larger size than the link, a plate pivotally mounted over each opening, each plate having a guide passage through which the link extends, fastening means normally restraining each plate from pivotal movement, said plates, when released from the fastening means, being movable laterally thereby permitting lateral movement of the link to disengage it from the cranks so that any selected one of the grate bars may be removed.

11. Combustion apparatus comprising an ash-pit, a plurality of grate bars extending transversely thereof, supporting elements disposed along each side of the ash-pit, said elements having an interfitting engagement with end portions of the grate bars, but permitting the latter to be lifted out of engagement with the elements, said interfitting engagement being provided by sockets and parts received therein, the socket at one end of each grate bar being substantially U-shaped and the other socket having a substantially cylindrical wall, a crank carried by each grate bar, and an op-

erating link articulated to the cranks and normally holding the bars in place, said link passing through an opening at the front of the ash-pit, the removal of the link from its normal position in the opening serving to move it out of its bar holding position whereupon any one of the bars may be lifted out of its operative position.

Signed by me at Westfield, Massachusetts,
10 this 20th day of May, 1929.

STANLEY K. SMITH.
